UNITED STATES PATENT OFFICE

97,429

DESIGN FOR AN AUTOMOBILE

Carl Breer, Grosse Pointe Park, and Oliver Hartington Clark, Detroit, Mich.

Application December 27, 1934, Serial No. 54,620

Term of patent 14 years

To all whom it may concern:

Be it known that we, Carl Breer and Oliver Hartington Clark, citizens of the United States, residing at 15600 Windmill Pointe, in the city of Grosse Pointe Park, and 18005 Fairfield Avenue, in the city of Detroit, respectively, county of Wayne, and State of Michigan, have invented a new, original, and ornamental Design for Automobiles, of which the following is a specification, reference being had to the accompanying drawing, forming part thereof, in which:

Fig. 1 is a side elevational view of an automobile showing our new design with the front portion illustrated in full lines, and illustrating the rear end and intermediate portions of the automobile in dotted lines.

Fig. 2 is a three-quarter front perspective view

of an automobile showing our new design with the front portion illustrated in full lines, and illustrating the rear end and intermediate portions of the automobile in dotted lines.

Fig. 3 is a front end view of an automobile showing our new design.

The dominant feature of our new design comprises the appearance of the front end portion, as illustrated in full lines. The intermediate and rear end portions shown in dotted lines (Figs. 1 and 2) are immaterial.

We claim:

The ornamental design for an automobile substantially as shown and described.

CARL BREER.

OLIVER HARTINGTON CLARK.
